UNITED STATES PATENT OFFICE

CHARLES F. SPRINGFELS, OF WEST PALM BEACH, FLORIDA

SAFETY TRAFFIC LIGHT

Application filed September 20, 1929. Serial No. 393,952.

This invention relates to a safety traffic light and more particularly to such a safety traffic light which is adapted for use at the intersections of through traffic highways at which crossings the traffic on the through traffic highway is given the right of way while vehicles crossing the highway are required to come to a complete stop before entering or crossing the through traffic highway. The invention can, however, be employed for other purposes such as at railroad crossing or other places.

The principal object of the present invention is to give a clear and unmistakable signal to the drivers from all directions at a crossing, the driver traversing the through traffic highway being given a cautioning signal and the driver on the intersecting street being given a warning to stop and then go when the through traffic highway is clear.

One of the objects of the present invention is to provide a low cost and durable safety traffic light of this character in which the warning lenses and other signs mounted in the same are adequately illuminated both at night and during the day.

A further purpose is to provide such a signal which is light in weight and can be quickly assembled or dismantled and in which any of the parts, particularly the electric bulbs, glass lenses and sign panels can be quickly and easily removed and replaced or changed.

Another purpose is to provide such a safety traffic light, the casing of which is formed of simple sheet metal stampings and the stampings are formed to provide light baffles or guards which conceal the signal lights at the sides from drivers approaching the signal from any direction, thereby preventing confusion from conflicting signalling indications.

Another purpose is to provide such a safety traffic light which brilliantly illuminates the roadway under and around the signal thereby making the intersection more safe for pedestrians. This illumination of the roadway is effected without any glare which would be offending to the eyes of the motorists.

A further aim is to provide a simple, strong and durable means for suspending the safety traffic light from a cross wire, which means also serve as a conduit for the electric wires and also support the plug which carries the electric bulbs.

Another purpose is to provide such a mounting which permits the safety traffic light casing to be shifted relative to the mounting so the safety traffic light can be hung in the most advantageous position at crossings which are not perpendicular to one another.

Another object is to provide a safety traffic light which has a number of illuminated panels which can bear any manner of informative or directional printed matter desired, such as directions to particular places or the street being crossed.

Another object is to provide such translucent lettered panels for such a safety traffic light which are easily lettered and which are entirely weather proof so that the lettering is not impaired by the elements.

Other objects are to provide such a safety traffic light which contains no moving parts, which is made entirely of sheet metal stampings and standard parts, is inexpensive to construct and maintain and which will withstand storms, snow and rain without getting out of order.

In the accompanying drawings:

Figure 1 is a side elevation of a safety traffic light embodying my invention viewed from one of the sides presented to the street crossing the through traffic highway.

Figure 2 is a similar view of the signal viewed from the through traffic highway.

Figure 3 is a top plan view thereof.

Figure 4 is a fragmentary vertical section taken on line 4-4, Fig. 3.

Figure 5 is a fragmentary perspective view of a part of the means for suspending the signal from a cross wire.

Figure 6 is a fragmentary perspective view of one of the translucent signs or glass panels showing the manner in which the edges are sealed to prevent weathering of the lettering.

Figures 7 and 8 are vertical sections taken

on the correspondingly numbered lines on Fig. 3.

Figure 9 is a fragmentary section taken on line 9—9, Fig. 1 and showing a corner of the signal casing.

Similar reference numerals refer to like parts in each view.

The signal is shown as suspended from a cable 10 which extends diagonally across the 10 street and is secured at its ends to posts or buildings in any suitable manner. It is apparent, however, that the light can be mounted in any one of a number of well known and usual ways, the invention not being confined 15 to any particular kind of supporting member.

The casing is composed of four sheet metal plates 11 and 12, the sides 11 being arranged to face the through traffic highway while the 20 sides 12 are arranged to face the intersecting street. These plates are identical in form and construction and hence a description of one will be deemed to apply to the others. Each of these sides 11 and 12 is composed of 25 a flat sheet metal plate which is flanged inwardly at its upper and lower edges as indicated at 13 and 14 and at its side edges is flanged diagonally outward as indicated at 15. These diagonal flanges 15 extend outwardly a substantial distance from the side 30 plate and are provided with openings which are adapted to receive bolts 16. In assembling the signal casings, the several side plates are arranged with their diagonal flanges 15 35 face to face so as to form a box-like structure and the bolts 16 are then passed through the flanges 15 so as to unite the several plates securely together. In this position the flanges 13 of the several plates overlap one 40 another at their ends and the flanges 14 at the lower edges of the several plates also overlap at their ends for a purpose which will presently appear.

In the central part of each side plate 11 45 or 12 a pair of circular openings 17 is provided behind which lenses 18 are mounted and above and below the lenses 18 a rectangular opening 19 is provided in each side plate behind which rectangular openings 50 translucent glass panels 20 are mounted. The lenses 18 and panels 20 are held in position in any suitable manner as by metal clips 21 which can be welded to the inner face of the side plates and embrace the edges of 55 each lens or panel.

One of the lenses on each of the side plates 11 facing the through traffic highway is preferably of a green color and bears a suitable cautionary legend such as the word "Slow" 60 and the other is preferably of a color contrasting with green such as white and can bear some information such as the speed limit along the through traffic highway. By this means the traffic on the through traffic highway is given a "go" signal, the color green

being universally recognized as a "go" indication, but its effect is modified by the presence of the white lens immediately adjacent thereto, thereby putting the traffic on guard that while it has the right of way, cross traffic might enter or cross against the signal. With only a green lens through traffic drivers would be liable to assume that the signal is a stop and go signal by which cross traffic is definitely held up until the signal 70 colors reverse and serious accidents might occur through this assumption. The presence of the white lens modifies this "go" indication, however, so that no confusion arises as to the intent of the signal.

In a similar manner one of the lenses in each of the side plates 12 facing the intersecting street is of a red color and preferably bears a warning indication such as the word "Stop" and the other is of a contrasting color such as white and can bear a warning legend such as "Thru traffic." As with the green lens, the white lenses in the side plates 12 modify the "Stop" effect of the red lens and indicate that only a modified stop 90 signal is intended and that after the stop has been made and an opening found in the through traffic that the driver is free to proceed into the through traffic highway.

The translucent glass panels 20 can bear 95 any suitable information or warnings. As illustrated, the upper panels bear the names of the streets at which the safety traffic light is located and the lower panels facing the through traffic can bear a warning such as 100 the word "Caution" and on the other sides the lower panels can bear the words "Go when road is clear" or like directions. To avoid weathering of the lettering, each of these panels is composed of a clear glass 105 front or outer pane 22 and a milk white or opal rear or inner pane 23. The letters 24 are preferably cut from tinfoil and are applied to the rear of the front pane 22 with any suitable adhesive. The two panes are 110 then placed face to face with the letters between them and a sealing layer 25 of Canadian balsam is applied to the edges of the two panes, a part of this running between the panes and sealing the same. After the 115 balsam has partially hardened, the edges of the two panes are coated with a second layer of Canadian balsam after which a band of silk 26 is wound around the edges, the Canadian balsam being sufficiently tacky to cause 120 the silk ribbon to adhere. A glass panel composed of two glass panes united in this manner will withstand exposure indefinitely and the edges of the two panes are effectively sealed against the entrance of rain or dirt.

The panels therefore remain in a clean opalescent condition and the letters are at all time clear cut and entirely legible. To increase the illumination of the sign the interior of the casing walls are preferably coated 125 130

with white enamel or paint while the outside has a dark finish.

The casing is suspended from a convex hood 27 which is spaced from the upper open end of the casing and extends outwardly therefrom so that the electric light within the casing, in addition to illuminating the lenses and panels and directly illuminating the roadway through the open bottom of the casing, is reflected downwardly by the white- or reflecting under surface of the hood 27 and around the sides of the casing as hereinafter described. The means for suspending the casing from the hood 27 include four rods 28 which are threaded at their opposite ends and pass through openings in the corners of the hood and openings provided at the opposite ends of the inwardly projecting flanges 13 and 14 at the places where the flanges 13 and 14 of the several side plates overlap. A pair of nuts 29 are arranged on opposite sides of the lower flanges 14 and securely unite each rod 28 to the lower part of the casing, a similar pair of nuts 30 secure each rod to the upper flanges 13 and a similar pair of nuts 31 secure the upper end of each rod 28 to the hood 27, each of these nuts being threaded on the rod 28. By this means the casing is suspended at its four corners from the hood 27 and the hood and casing are reliably held in fixed spaced relation. This construction is also very quickly assembled.

A threaded pipe or conduit 32 extends centrally through the hood 27, and is secured thereto by a pair of nuts 33 which are tightened against the upper and under sides of the hood. To reinforce the hood around its connection to the pipe 32, a circular plate or washer 34 is preferably interposed between the lower nut 33 and the under side of the hood. At the lower end of the pipe or conduit 32, an electrical socket 35 is secured in any suitable manner and in this socket is screwed a four-way plug 36, this plug and socket being of any well known form and the four-way plug being provided with four electric bulbs 37. The filaments of these bulbs are preferably arranged about on a level with the lenses 18 and are preferably arranged, as indicated in Fig. 8, so that a bulb is directly behind each of the lenses.

A T-coupling 38 is screwed onto the end of the pipe 32 projecting upwardly from the hood 27, and in the arms of this T-coupling, branch pipes 39 are screwed, these branch pipes being closed at their ends by caps 40. A hole is drilled in one of the caps 40 and the electric wire 41, which is suspended from the cable 10 by clips 42, passes through this hole, and through the corresponding arm or branch pipe 39, T-coupling 39, and pipe 32 to the socket 35 to which it connects.

To suspend the signal from the cable 10, a pair of wire clamps are provided each of

which embraces the cable and one of the branch pipes or arms 39 and securely holds these parts together. Each of these clamps consists of a U-shaped bail or yoke 42 which is threaded at its opposite ends and the legs of which are adapted to depend and straddle the cable 10 and one of the branch pipes 39. The legs of each of these bails pass through holes provided in a cross plate 43 and this cross plate 43 is tightened against the under side of the corresponding branch pipe 39 by a pair of nuts 44 threaded on the ends of the bail. Upon tightening the nuts 44 the cable 10 and the branch pipes 39 are clamped between the bails and the cross plates and the signal is reliably suspended from the cable 10.

It has been found advisable, to protect the signal during hurricanes and gales, that additional reinforcing means be provided between the hood 27 and the pipes which carry it. For this purpose a strap 45 is provided which is secured at its ends to the top of the hood 27 by bolts 46 and extends over and embraces the T-coupling 38, as best shown in Fig. 5. Each of the bolts 46 passes through a slot 47 in the corresponding end of the strap 45 and also through a registering slot 48 in the hood, and the nut of each bolt 46 bears against a reinforcing plate 49 on the under side of the hood. The slots 47 and 48 are arranged circumferentially to the pipe 32 and hence it is apparent that a limited turning movement of the safety traffic light casing can be obtained relative to the cable 10 before the connections are tightened. Thus assume that the signal is to be placed at a crossing where the streets are not perpendicular to one another and it is desirable to have the signal set at an angle to its supporting cable 10, before the upper nut 33 and the bolts 46 are tightened, the signal is turned to the desired angle, the bolts 46 riding along the slots 47 and 48. When the signal is set at the desired angle, the upper nut 33 is tightened against the upper side of the hood 27 and the nuts 46 are tightened to secure the strap 45 rigidly in place.

From the foregoing it is apparent that this invention provides a safety traffic light which is inexpensive to form and assemble and can be quickly and readily set up or any of the parts replaced. The signal is also durable in construction, has a low maintenance cost and will withstand windstorms, rain and snow without getting out of order or diminishing its effectiveness. The signal also adequately illuminates the roadway under the same both through the direct light from the four bulbs and also through the reflected light from the hood around the outside of the casing. The light casing is also so formed that the signal lenses at the side of the casing are concealed from approaching traffic and the signal lenses and panels are so ar-

ranged as to indicate clearly what the driver is to do thereby avoiding confusion and possible accidents.

I claim as my invention:

- 5 1. A safety traffic light including a casing having an open upper end, a hood arranged over said casing and spaced therefrom, illuminating means arranged in said casing, signalling means arranged in the walls of said casing and illuminated by said illuminating means, the edges of said hood extending laterally beyond said casing whereby the light from said casing passes from said illuminating means between said casing and hood and is reflected downwardly around said casing by the marginal parts of said hood and means for suspending said casing from said hood comprising a plurality of rods depending from said hood and passing through openings provided in said hood and casing and means for rigidly and independently connecting said rods to said hood and casing.
- 10 2. A safety traffic light including a casing composed of sheet metal sections having overlapping parts, a hood arranged over said casing, illuminating means arranged in said casing, signalling means arranged in the walls of said casing and illuminated by said illuminating means, and means for suspending said casing from said hood comprising rods passing through the overlapping parts of said casing and secured thereto and means for connecting said rods to said hood.
- 15 3. A safety traffic light including a casing composed of sheet metal side sections having inwardly projecting horizontal flanges, the flanges of said sections being adapted to overlap one another at their ends, a hood arranged over said casing and spaced therefrom, illuminating means arranged in said casing, signalling means arranged in the walls of said casing and illuminated by said illuminating means, and means for suspending said casing from said hood and in fixed relation thereto, comprising threaded rods passing through the overlapping parts of said flanges and through said hood and nuts screwed on said rods and engaging the overlapping parts of said flanges and said hood.
- 20 4. A safety traffic light including a casing composed of sheet metal side sections, means for securing said sections together, at least two of said sections being formed to provide vertical diagonally outward projecting flanges at the vertical corners of said casing, illuminating means arranged in said casing, translucent signalling means in said sections, said translucent signalling means being adapted to give different signalling indications on different sides of said casing, said diagonal flanges extending a sufficient distance to conceal the right and left sides of the casing from one approaching the safety traffic light from any side of the same.
- 25 5. A safety traffic light including a casing

composed of four sheet metal side sections, each of said sections being formed to provide diagonally outward projecting flanges, the flanges of adjacent sections being adapted to be arranged face-to-face and forming diagonally outward projecting flanges at the corners of said casing, fastenings extending through and uniting the flanges of the several sections, illuminating means arranged in said casing, translucent signalling means in said sections, said translucent signalling means being adapted to give different signalling indications on different sides of said casing, said diagonal flanges extending a sufficient distance to conceal the right and left sides of the casing from one approaching the safety traffic light from any side of the same.

6. A safety traffic light including a casing composed of four sheet metal side sections each having inwardly projecting flanges at its upper and lower edges and diagonally outward projecting flanges at its opposite vertical edges, the horizontal flanges of the several sections being adapted to overlap one another at their ends and said diagonal flanges being adapted to be arranged face-to-face and forming diagonally outward projecting flanges at the corners of said casing, fastenings extending through and uniting the diagonal flanges of the several sections, a hood arranged over said casing and spaced therefrom, illuminating means arranged in said casing, signalling means in the walls of said casing and illuminated by said illuminating means and means for suspending said casing from said hood in fixed relation thereto, comprising threaded rods passing through the overlapping parts of said horizontal flanges and through said hood and nuts screwed on said rods and engaging the overlapping parts of said flanges and said hood.

7. A safety traffic light adapted to be suspended from a fixed support comprising a vertical pipe threaded at its upper end, a T-fitting screwed on the upper end of said pipe, branch pipes screwed into said T-fitting, means for securing said branch pipes to said support, a hood secured to said pipe, said pipe passing centrally through said hood and said hood being held between two nuts on said pipe, a casing suspended from said hood, translucent signalling means in the walls of said casing, an electric light bulb at the lower end of said pipe within said casing and illuminating said signalling means, and a strap secured at its opposite ends to said hood and passing over said T-fitting.

8. A safety traffic light adapted to be suspended from a fixed support, comprising a vertical pipe threaded at its upper end, a T-fitting screwed on the upper end of said pipe, branch pipes secured to said T-fitting, means for securing said branch pipe to said support, a hood secured to said pipe, said

pipe passing centrally through said hood and said hood being held between two nuts on said pipe, a strap extending over said T-fitting and provided with transverse slots at 5 its opposite ends, said hood being provided with similar slots adapted to register with the slots in said strap, bolts arranged in said slots and securing the ends of said strap to said hood but permitting said hood to be moved adjustably relative to said branch 10 pipes, a casing suspended from said hood, translucent signalling means in the walls of said casing and an electric light bulb at the lower end of said pipe within said casing 15 and illuminating said signalling means.

9. A safety traffic light including a casing having an open upper end, a hood arranged over said casing and spaced therefrom, illuminating means arranged in said casing, signalling means arranged in the walls of said 20 casing and illuminated by said illuminating means, and means for suspending said casing from said hood comprising a plurality of rods depending from said hood and passing 25 through openings provided in said hood and casing and means for rigidly and independently connecting said rods to said hood and casing.

In testimony whereof I hereby affix my 30 signature.

CHARLES F. SPRINGFELS.
